UNITED STATES PATENT OFFICE.

WILLIAM MOORE THOMPSON, OF CHICAGO, ILLINOIS.

ANTI-THUMB-SUCKING DEVICE.

Application filed October 13, 1924. Serial No. 743,297.

My present invention relates to improvements in antithumb sucking devices, and the main object of my invention is the provision of an improved construction of this kind which will be highly practical and efficient in use, and which embodies features designed to enable the device readily to be fitted on and adjusted to infants' hands of different sizes.

10 Other objects will appear hereinafter.

The invention consists in the combinations and arrangements of parts hereinafter described and claimed.

15 The invention will be best understood by reference to the accompanying drawings forming a part of this specification, and in which,

20 Fig. 1 represents a hand in front or palm elevation with my improved device applied thereto;

Fig. 2 represents an elevation of the back of a hand showing my improvements as applied thereto;

25 Fig. 3 is a fragmentary view, illustrating how the flexible securing element may, after passing around the wrist be secured upon itself in various adjusted positions;

Fig. 4 is an end view of the thumb engaging member, this view being taken approximately on the line 4-4 of Fig. 1;

30 Fig. 5 is a detail view, illustrating in particular the angular divergence of the flexible connections for the thimble at the front or palm side of the thumb; and

35 Fig. 6 is an enlarged end view of the thimble.

The preferred form of construction as illustrated in the accompanying drawing includes a thumb engaging member, referred to generally at 7, and consisting of a split ring 8 formed with spaced apart radial projections 9 of the form best shown in Fig. 4.

40 Each of the radial projections 9 is provided at its outer or free end with an aperture 10.

45 Where the extremities 11 of the split ring overlap as shown there is no radial projection 9, but the overlapping ends are preferably formed with outwardly projecting flanges 12 which come in sliding engagement, one over the other, and which are provided with apertures 13, designed to register and to receive means (not shown) for securing together the extremities of the split ring in the adjusted position desired.

55 Fig. 14 denotes as a whole a thimble member which is designed to envelop the tip por-

tion 15 of the thumb member as 16. This thimble member is preferably made in the skeleton form shown, the same comprising a tip ring 17 which fits on the end of the thumb and from which project over the thumb towards the joint 18 thereof radial strips 19 to which is attached by means of solder or otherwise a ring portion 20. This thimble member is preferably stamped from a blank 60 of material so as to produce the tip ring 17 and the radially extending strips 19, of which two strips in opposed relation are made longer than the others so that they may be bent outwardly upon themselves alongside 65 of the ring or band 20 in order to produce loops 21 and 22 with which the flexible connections may be engaged as will presently appear.

70 The thumb engaging member 7 is applied to the thumb of the infant so as to occupy a position upon the waist-shaped region 23 of the thumb beyond the joint 18, this thumb engaging member being thus applied with the overlapping flanges 12 on the front or palm side of the thumb. 24 represents a flexible member, preferably a chain, which connects a circular link 25 applied to the loop 21, with another circular link 26 carried on the extremity of a securing chain 27 which is passed about the wrist of the wearer and is thence engaged with itself, being for this purpose provided with a hook member 28 of a size adapted to be engaged with any one of the links making up the chain. The 75 flexible connection 24 extends as best shown in Fig. 2 longitudinally of the thumb upon the back thereof and is passed through an aperture 10 of a radial projection 9. To the loop 22, which comes directly opposite the loop 21, there is applied a circular link 29 with which are engaged the extremities of a flexible connection 30, also preferably consisting of a chain. This flexible connection extends through an aperture 10 of a radial projection 9, thence through the circular link 26 and thence through the aperture of another radial projection 9, the said flexible member preferably passing through the apertures of the radial projections which come adjacent to the overlying flanges 12 on opposite sides thereof as best illustrated in Fig. 4. The thimble 14 is thus securely held upon the tip of the thumb by means of the flexible connections 24 and 30, the first 80 mentioned extending along the back of the thumb longitudinally thereof and supported 85

100

105

110

upon the thumb engaging ring, while the second mentioned extends in diverging relation from the front or palm side of the thumb to the thumb engaging ring on the sides whereof it is supported and thence continues in converging relation to the circular link 26 through which it passes. By means of this arrangement the thumb is provided with means which soon discourages the infant in its practice, and at the same time it is free to be flexed without restraint in any natural direction. In Fig. 3 the securing chain 27 is illustrated as being passed around the wrist of the wearer, then being passed about or tied upon itself before the hook 28 is engaged in a link. Obviously, before the hook is engaged with a link, the chain may be drawn or tied upon itself with a degree of tightness desired. In this manner the chain may be readily adjusted upon the hands of infants which differ considerably in size.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. The combination of a thumb engaging ring, a thimble for the tip of the thumb, and chains extending from the thimble to the ring for holding the thimble in operative position, substantially as described.
2. The combination of a thumb engaging ring, a thimble for the tip of the thumb, and means for engaging the wrist to hold said ring and thimble in operative position, substantially as described.
3. The combination with a thumb engaging ring, of a thimble for the tip of the thumb, apertured projections on said ring, and chains on the thimble taken through the apertures of the ring and adapted to be fastened on the wrist, substantially as described.
4. The combination of a ring having radial projections, with openings, a thimble

member, connections between said thimble member and said radial projections, and means consisting of a continuation common to said connections, adapted to be connected around the wrist of the wearer, substantially as described.

5. The combination of a ring having projections with openings therein, a thimble member, flexible connections attached to the thimble member and passing through said openings and having a common connection adapted to pass around the wrist of the wearer, substantially as described.

6. In a device of the class described, the combination with a ring having radial projections with openings therein, of a thimble member adapted to envelop the tip of the thumb and having integral loops thereon, flexible connections engaged in said loops and extending through the openings in said radial projections, and a flexible wrist encircling element with which said flexible connections are engaged at one point, substantially as described.

7. In a device of the class described, the combination with a split ring having projections with openings therein, said ring being adapted to encircle the thumb behind the first joint thereof, of a thimble member adapted to envelop the tip of the thumb and provided with loops, flexible connections engaged in said loops and extending through said openings, and a securing arrangement with which the flexible connections are connected, adapted to be clasped about the wrist of the wearer, substantially as described.

8. In a device of the class described, the combination with a ring having lateral projections with openings therein, of a thimble member adapted to envelop the tip of the thumb and having oppositely disposed loops, a securing element with a link, a chain having its extremities attached to one of said loops passing through two of said openings and through said link, and a chain connecting the opposite loop with said link, said last mentioned chain passing through an opening approximately equally distant from the openings through which said first chain passes, substantially as described.

In testimony whereof I have signed my name to this specification.

WILLIAM MOORE THOMPSON, M. D.
